United States Patent Office

Des. 193,900
Patented Oct. 23, 1962

193,900

END LINK FOR A BRACELET OR SIMILAR ARTICLE

Karl C. Augenstein, Cranston, R.I., assignor to Speidel
Corporation, Providence, R.I., a corporation of Rhode
Island

Filed Mar. 20, 1962, Ser. No. 69,341

Term of patent 14 years

(Cl. D45—4)

FIG. 1

FIG. 2

FIG. 3

FIG. 4

FIG. 5

FIG. 1 is a top plan view of an end link for a bracelet or similar article showing my new design;

FIG. 2 is a side elevational view;

FIG. 3 is an end elevational view looking from the left of FIG. 1;

FIG. 4 is an end elevational view looking from the right of FIG. 1; and

FIG. 5 is an enlarged perspective view thereof.

I claim:

The ornamental design for an end link for a bracelet or similar article, substantially as shown.
